UNITED STATES PATENT OFFICE.

MARSILIO BUTI, OF POINT ARENA, CALIFORNIA.

ARCH SUPPORT.

Application filed December 27, 1926. Serial No. 157,168.

This invention aims to provide an arch support for the foot which may be fashioned cheaply out of leather or any other suitable material, it being possible to shape the support readily to suit the peculiarities of the particular case that is being treated, novel means being provided for holding the support in the desired shape.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in top plan, a device constructed in accordance with the invention;

Figure 2 is a side elevation;

Figure 3 is a bottom plan;

Figure 4 is a section on the line 4—4 of Figure 2.

The arch support forming the subject matter of this application comprises a main section 1, preferably made of leather. The main section 1 is shaped peripherally at 2, curved longitudinally at 3, and curved transversely at 4, as the pathology of the particular case may demand. In the lower surface of the main section 1, there is formed a main recess 5 bounded by a shoulder 6 disposed approximately at right angles to the lower surface 7 of the main section 1. Above the main section 1 there is fashioned an auxiliary recess 8 of less extent than the main recess 5, both of the recesses 5 and 8 opening through one side of the main section 1, as shown in Figures 2 and 4, below the upwardly extended, skived side wing 9 that exists along one edge of the main section 1. The auxiliary recess 8 is located above the main recess 5 and is in communication with the main recess.

In the main recess 5 is located a tie plate 10, which, preferably, is made of leather and fits against the peripheral shoulder 6 of the main recess. The tie plate 10 is connected by stitching 11 with the main section 1, and the main section 1, together with

the tie plate 10, are slit to receive the stitching 11, the slitting being marked by the numeral 12, and the construction being such that the tie plate is blind-stitched to the main section 1, the lower surface of the tie plate 10 being disposed flush with the lower surface 7 of the main section 1, so that there are no projections on the bottom of the article. The plate 10 is called a tie plate, because it acts like a tie in a truss, and aids in retaining the main section 1 in the curved form shown at 3 and at 4. If desired, the auxiliary recess 8 may be occupied by a filler 14, generally made of metal, and connected by a rivet 15 or otherwise to the tie plate 10, the head of the rivet being let into the lower surface of the tie plate, as shown at 16, so that the lower surface of the tie plate presents no projections.

The device forming the subject matter of this application is not a part of a shoe or other article of footwear: consequently, it can be used in connection with any kind of shoe, and may be shifted readily from one pair of shoes to another. The article is so made that it will wear a long time. It presents a large surface, and will not creep. It can easily be placed in a shoe and shaped to conform with the arch of the foot being inserted into the shoe. The device comprises but few parts and may be manufactured cheaply. The device has a smooth surface both on its upper side and on its lower side, and there are no projections, ridges, or lumps to chafe or irritate the wearer.

What is claimed is:—

In an arch support, a main section curved both longitudinally and transversely, and provided in its lower surface with a main recess, the main section having an auxiliary recess of less extent than the main recess, the auxiliary recess being disposed above the main recess and in communication with the main recess, a tie plate of materially less area than the main section, the tie plate being located in the main recess and forming a complete closure for the bottom of the main recess, means for securing the tie plate adjacent to its periphery to the main section, thereby to hold the main section curved as aforesaid, a filler in the auxiliary recess, and means for securing the filler to the tie plate independently of the main section.

In testimony that I claim the foregoing as my own, I have hereto affixed my signature.

MARSILIO BUTI.
